US0D1011394S

(12) **United States Design Patent** (10) Patent No.: **US D1,011,394 S**
(45) Date of Patent: ** Jan. 16, 2024

(54) **CUTTING MACHINE**

(71) Applicant: **Mobile Outfitters US Inc.**,
Philadelphia, PA (US)

(72) Inventors: **Phillip Chang**, Philadelphia, PA (US);
Dennis O'Donnell, Philadelphia, PA (US)

(73) Assignee: **Mobile Outfitters US Inc.**

(**) Term: **15 Years**

(21) Appl. No.: **29/878,525**

(22) Filed: **Jun. 23, 2023**

(51) LOC (14) Cl. **15-09**

(52) U.S. Cl.

(57) **CLAIM**

The ornamental design for a cutting machine, as shown and described.

DESCRIPTION

FIG. 1 is a front perspective view of a cutting machine according to our new design;

FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines illustrating portions of the cutting machine form no part of the claimed design.

1 Claim, 8 Drawing Sheets
